UNITED STATES PATENT OFFICE

JAMES WAKEFIELD, OF COCKERMOUTH, ENGLAND

PROCESS FOR THE DYEING OF VAT COLORS ON FABRICS

No Drawing. Application filed May 21, 1928, Serial No. 279,619, and in Great Britain June 23, 1927.

This invention relates to an improved process for the dyeing of vat colors, indigo, sulphur colors and mineral khaki colors, on fabrics or other piece goods.

5 The process according to the invention consists in batching the material through water containing a small quantity of caustic soda and sodium hydrosulfite, running them into an open width bleaching kier, pumping the 10 dye liquor into the kier, running the material a number of times through the dye liquor, emptying the kier of dye liquor, washing the material in the kier with water containing a small quantity of sodium hydrosulfite, again 15 emptying the machine, pumping a developing liquid into the kier and running the material in the developing liquid until the color is fully developed, the whole process being carried out without removing the material from 20 the kier.

In carrying out the invention the fabric or piece goods are scoured and bleached in the usual way and are then batched through water containing a small quantity of caustic soda 25 and sodium hydrosulfite after which they are run into an open width bleaching kier and the lid or cover of the latter screwed on. The kier is then exhausted of air by blowing steam into it.

30 The dye bath is prepared in a separate tank connected by a pipe or pipes which the kier into which the dye liquor can be forced by a pump. In preparing the dye bath it is essential that it should be a well reduced bath.

35 The material is then started running in the kier and the dye liquor pumped into the machine, six to twelve ends being given according to the dyestuff used and the depth of color required. The pump is then reversed and the 40 machine emptied of dye liquor.

As soon as the kier is empty a washing water containing a small quantity of sodium hydrosulfite is pumped into the kier from a second tank and two ends of the material are given.

45 The machine is again emptied and a developing bath of bichromate, perborate or other oxidizing agent is pumped in from a third tank.

The material is run in this bath a sufficient time to thoroughly develop the color after 50 which the material is taken out, soured (if

necessary) and soaped in open machine, the main kier being then ready for a fresh batch of material.

With the process above described the material is kept continuously in motion from the 55 time the dyestuff first enters the kier until it is fully developed and at the same time the material is kept out of all contact with the air whereby a good level dyeing is obtained. The process also effects a saving in chemicals and 60 allows dealing with large batches of material.

What I claim as my invention and desire to protect by Letters Patent is:—

1. Process for the dyeing of vat colors, indigo, sulphur colors and mineral khaki colors 65 on fabrics or other piece goods consisting in batching the material through water containing a small quantity of caustic soda and sodium hydrosulfite, running them into an open width bleaching kier, pumping a dye 70 liquor into the kier, running the material a number of times through the dye liquor, emptying the kier of dye liquor, washing the material in the kier with water, again emptying the machine, pumping a developing liquid 75 into the kier and running the material in the developing liquid until the color is fully developed, the whole process being carried out without removing the material from the kier.

2. Process for the dyeing of vat colors, indigo, sulphur colors and mineral khaki colors on fabrics or other piece goods consisting in batching the material through water containing a small quantity of caustic soda and sodium hydrosulfite, running them into an open width bleaching kier, pumping a dye liquor 85 into the kier, running the material a number of times through the dye liquor, emptying the kier of dye liquor, washing the material in the kier with water containing a small quantity of sodium hydrosulfite, again emptying the machine pumping a developing liquid into the kier and running the material in the developing liquid until the color is fully developed, the whole process being carried out without removing the material from the kier.

3. Process for the dyeing of vat colors, indigo, sulphur colors and mineral khaki colors on fabrics or other piece goods consisting in 100

batching the material through water containing a small quantity of caustic soda and sodium hydrosulfite, running them into an open width bleaching kier, preparing the dye bath in a separate tank, pumping the dye liquor into the kier, running the material a number of times through the dye liquor, emptying the kier of dye liquor, washing the material in the kier with water, again emptying the machine, pumping a developing liquid into the kier and running the material in the developing liquid until the color is fully developed, the whole process being carried out without removing the material from the kier.

15 In testimony whereof I have hereunto set my hand.

JAMES WAKEFIELD.
